UNITED STATES PATENT OFFICE.

FRANKLIN P. McELFRESH, OF ELK HORN, IOWA.

TRUSS.

1,341,333.

Specification of Letters Patent.

Patented May 25, 1920.

Application filed February 17, 1919. Serial No. 277,488.

To all whom it may concern:

Be it known that I, FRANKLIN P. McELFRESH, a citizen of the United States, residing at Elk Horn, in the county of Shelby 5 and State of Iowa, have invented a new and useful Truss, of which the following is a specification.

The device forming the subject matter of this application is a truss, and the invention 10 aims to provide a truss having no elastic parts likely to decay, the truss being devoid of a perineal strap.

The invention aims to provide novel 15 means whereby the pads may be adjusted circumferentially of the body encircling belt, and, as well, be adjusted longitudinally of the body of the wearer.

Another object of the invention is so to construct the belt or band of the truss, that 20 the belt may be located high enough up so as not to interfere with the operation of walking, the height of the belt permitting the same to clear the hip bones, thereby avoiding a raising of the belt and a releasing 25 of the rupture.

The invention aims to provide a truss including a belt which will produce no unnecessary circumferential pressure on the body of the wearer, there being, merely, 30 enough pressure to prevent the truss from slipping.

Another object of the invention is to improve the construction of the truss pad.

It is within the province of the disclosure 35 to improve generally and to enhance the utility of devices of that type to which the invention appertains.

With the above and other objects in view, which will appear as the description 40 proceeds, the invention resides in the combination and arrangement of parts and in the details of construction hereinafter described and claimed, it being understood that, within the scope of what is claimed, changes 45 in the precise embodiment of the invention shown can be made without departing from the spirit of the invention.

In the drawings:—

Figure 1 shows in top plan, a truss constructed in accordance with the invention;

Fig. 2 is a side elevation of the truss; Fig. 3 is a front elevation of the truss; Fig. 4 is an elevation showing the pad; Fig. 5 is a cross section of the pad, a portion of the supporting arm for the pad appearing; Fig. 55 6 is a sectional view showing a portion of the pad; and Fig. 7 is a section on the line 7—7 of Fig. 3.

The device forming the subject matter of this application comprises a belt, one 60 part of which is represented by a body 1, preferably made of metal. The belt includes arms 2 located approximately in a common plane with the body 1 and secured to the ends of the body, as shown at 3, the 65 arms 2 having depending ends 4. The arms 2 preferably are made of metal. The belt may be bent to fit the wearer.

Since the ends 4 depend as above mentioned, the belt may be located high enough 70 up on the body of the wearer so as not to interfere with the operation of walking. Again, since the belt may be located at a considerable elevation above the rupture, the hip bones will not be likely to raise the 75 belt and detach the pads, hereinafter described, from the rupture.

A flexible lining 5, made of leather or any other desired material, extends circumferentially of the body 1, the arms 2 and the ends 80 4, and is attached to these parts by securing elements 6. In the ends 4, there are openings 7, adapted to receive hooks 8 or like elements, united by securing members 9 with the parts of a flexible back strap 10, the 85 members of which are united by a buckle 11 or otherwise.

The truss may be employed for retaining either a single rupture or a double rupture. Assuming that a double rupture is to be retained, longitudinal slots 12 are fashioned 90 in the body 1 of the belt. Slides 14, in the form of plates are adapted to reciprocate on the outer surface of the body 1 at the slots 12. The upper ends of strips 15 are 95 attached by securing members 16 to the forward surfaces of the slides 14, the strips 15 constituting parts of pad supporting arms. Bolts 17 are located in the slots 12 and pass through the slides 14, the bolts having heads 100

18 engaging the inner surface of the body 1, as clearly shown in Fig. 7, the heads being supplied with screw driver kerfs 19, if desired. The outer ends of the bolts 17 are 5 threaded into nuts 20, abutting against the outer surfaces of the slides 14. It is to be observed that the nuts 20 coöperate with the strips 15 and are thus held against rotation. The lining 5 may be sprung inwardly away 10 from the body 1, thus giving access to the heads 18 of the bolts 17, and, by loosening the bolts, the slides 14 may be adjusted circumferentially of the body encircling belt, carrying with them, the pads hereinafter 15 described.

The pad supporting arms comprise lower strips 21 overlapped on the strips 15 and supplied with longitudinal slots 22 wherein are located clamp screws 23 threaded into 20 the strips 15 and having heads coöperating with the strips 21. Guides 24 are secured at 25 to the upper ends of the strips 21 and coact with the strips 15. By loosening the clamp screws 23, the lower strip 21 may be 30 slid upwardly and downwardly on the upper strips 15, and be held in adjusted positions by tightening up the clamp screws 23. In this way, the pads may be raised and lowered, and, since the arms 15—21 may 35 be adjusted circumferentially of the body 1 of the belt, it will be seen that the pads may be moved longitudinally of the corpus of the wearer or circumferentially thereof.

Each pad, comprises, preferably, an outer 35 plate 26, an inner plate 27 and an intermediate plate 28, the said plates being held together by screws 29 or otherwise, the intermediate plate 27 being of smaller diameter than the plates 26 and 28, thereby to form a 40 circumscribing groove 38. The intermediate plate 28 is supplied with a polygonal recess 30 wherein is seated, against rotation, a nut 31, held in the recess by the plates 26 and 27. The plates 26, 27 and 28 may be 45 fashioned from leather or any other suitable material which will not deteriorate in the presence of moisture and there is, therefore, a very good reason for providing a means whereby the nut 31, which ordinarily is 50 made of metal, may be held in place as above described. A screw 32 passes through the outer plate 26 and is threaded into the nut 20, the screw serving to hold the pad on the lower end of the strip 21 of the pad supporting arm. The numeral 33 denotes a flexible 55 cover, held by a draw string 34 or otherwise in the groove 38. A filler 35 is disposed within the cover 33, the filler preferably consisting of sand, this material being selected 60 because it will shape itself readily to the rupture and will not become foul or deteriorate, due to moisture. There is an opening 36 in the inner plate 29, alined with the opening in the nut 31 through which the

screw 32 passes. Thus, when the screw 32 65 is removed, the quantity of sand within the cover 33 may be regulated, to adjust the stiffness of the pad. In order to prevent the sand from working into the threads of the screw 32, or into the threaded aperture of 70 the nut 31, a closure 37 is placed in the opening 36 of the plate 27, this closure ordinarily being of pledge cotton, which can be pulled out with a pair of tweezers or like instrument, when the quantity of sand with- 75 in the cover 33 is to be changed.

The operation of the structure has been dealt with hereinbefore, in connection with the description of the various parts, but, by way of résumé, it may be noted that, owing 80 to the specific shape of the belt, including the parts 1, 2 and 4, the belt may be located at a relatively high elevation, thereby preventing a displacement of the belt and the pads while the wearer is walking or under 85 other conditions. The pad supporting arms may be adjusted circumferentially of the body encircling belt, and the pads may be raised and lowered by varying the lengths of the pad supporting arms. Consequently, 90 a wide range of adjustment for the pads is possible. The stiffness of the pads may be varied by adjusting the amount of sand or other filler 35 therein, as hereinbefore explained. 95

Having thus described the invention, what is claimed is:—

1. A truss pad including an outer plate; an inner plate having an opening; an intermediate plate between the inner and outer 100 plates and of less diameter than said plates, to define a groove, the intermediate plate being provided with a polygonal recess; a nut seated in the recess and held therein by the inner and outer plates; a screw threaded 105 into the nut; a cover engaged in the groove; and a granular filler located within the cover, the filler being insertible into the cover through the opening in the inner plate; and a closure for the opening, the closure being independent of the screw and constituting means for preventing the filler from working into the threads of the screw-receiving opening in the nut. 110

2. A truss comprising a body encircling 115 member having a longitudinal slot; a slide mounted to reciprocate on one surface of the body encircling member at the slot; an arm secured to the slide and outstanding therefrom; a nut coöperating with the slide and held against rotation by engagement with one edge of the arm; a bolt threaded into 120 the nut and passing through the slot, the nut having a head coöperating with the opposite surface of the body encircling member; and a pad supported by the arm. 125

3. A truss pad including an outer plate; an inner plate; an intermediate plate be-

tween the inner and outer plates and of less diameter than the said plates, to define a groove, the intermediate plate being provided with a polygonal recess; a nut seated 5 in the recess and held therein by the inner and outer plates; a screw threaded into the nut; a cover engaged in the groove; and a filler within the cover.

In testimony that I claim the foregoing as my own, I have hereto affixed my signature in the presence of two witnesses.

FRANKLIN P. McELFRESH.
